UNITED STATES PATENT OFFICE.

WILLIAM I. KENISON, OF NILES, KANSAS.

CROSS-LINE BUCKLE.

No. 798,135

Specification of Letters Patent.

Patented Aug. 29, 1905.

Application filed April 12, 1905. Serial No. 255,219.

To all whom it may concern:

Be it known that I, WILLIAM I. KENISON, a citizen of the United States, residing at Niles, in the county of Ottawa and State of Kansas, have invented certain new and useful Improvements in Cross-Line Buckles, of which the following is a specification.

This invention relates to cross-line buckles, and has for its object to produce a device of this character which shall be extremely simple in construction and which can therefore be manufactured and placed upon the market at a nominal cost.

Reference is to be had to the accompanying drawings, in which—

Figure 1 is a perspective view of the buckle in use. Fig. 2 is a bottom plan view. Fig. 3 is a vertical longitudinal sectional view. Fig. 4 is a similar view showing the link in an open position. Fig. 5 is a detail view of the link.

Corresponding and like parts are referred to in the following description and indicated in all the views of the drawings by the same reference characters.

The frame 1 of the buckle is made in the usual manner, except that instead of the customary cross-bar it is provided with two lugs 2, which project a short distance inwardly from each side. A piece of spring metal 4, provided with a perforation 5, is riveted or otherwise fastened to the under side of one of the cross-bars at one end of the buckle, so that the opening 5 is approximately over the lugs 2. The link member 6 is formed of a piece of looped metal, the ends of which are so bent as to form hooks 7, the upper portions of which are connected by a cross-bar 8. This cross-bar 8 is provided centrally with an upwardly-projecting stud 9. When the two parts are assembled, the hooks 7 are adapted to engage the lugs 2, and the stud 9 to pass through the opening 5 in the piece of spring metal 4.

The operation of the device is as follows: The long rein is passed through the buckle-frame 1 in the usual manner, passing between the piece of spring metal 4 and the lugs 2. The short rein is to be fastened to the link 6.

The hooks 7 are then placed in engagement with the lugs 2 and the whole turned around

said lugs as an axis until the stud 9 passes through the desired perforation in the long rein and is locked in position by passing through the opening 5 in the piece of spring metal 4. 55 When it is desired to remove the link 6 or adjust the short rein upon the long rein, the spring member 4 is lifted from the stud 9 and the link 6 turned around until the hooks 7 can be readily lifted off of the studs 2. The frame 60 1 can then be readily moved to any desired point on the long rein and then again fastened as heretofore described, or, if desirable, the link 6, to which the short rein is attached, can be detached from the frame 1. The use 65 of the lugs 2 enables the entire buckle to be detached from the long rein when desired by working the strap out between the lugs. It will thus be understood that I have invented an extremely simple device which is at the 70 same time very effective in operation and which can be cheaply manufactured.

Having thus described the invention, what is claimed as new is—

1. In a cross-line buckle, the combination 75 of the usual buckle-frame comprising side bars and connecting cross-bars, a strap-connecting link pivotally connected to said side bars at an intermediate point and having an upwardly-projecting stud thereon, and a 80 spring member carried by the frame and co-operating with said stud to hold the strap in position.

2. In a cross-line buckle, the combination 85 of the usual buckle-frame comprising side bars and connecting cross-bars, a link pivotally connected to said side bars at an intermediate point and having an upwardly-projecting stud thereon, and a spring attached 90 to one of the cross-bars and co-operating with said stud to hold the strap in position, said spring having a perforation therein through which the stud passes.

3. In a cross-line buckle, the combination 95 of the usual buckle-frame comprising side bars and connecting cross-bars, a link pivotally connected to the frame and having an upwardly-projecting stud thereon, and a spring attached to the frame and engaging said stud to hold the strap in position. 100

4. In a cross-line buckle, the combination of the usual buckle-frame comprising side

bars and connecting cross-bars, a link pivotally connected with the frame and having an upwardly - projecting stud thereon, and a spring carried by the frame and coöperating with said stud to hold the strap in position, said spring having an opening therein through which the stud is adapted to pass.

In testimony whereof I affix my signature in presence of two witnesses.

WILLIAM I. KENISON. [L. S.]
